7 Claims. (Cl. 61—16)

This invention relates to a development for the prevention of excessive wear on culverts, particularly culverts extending between lock chambers and having sharply descending portions therein.

An object of the present invention is to cause a back pressure in the culvert, particularly in any sharply inclined portion thereof in order to prevent the formation of a vacuum which is a factor in causing continual wearing of the culvert wall. It is known that as much as 18 inches of concrete in a culvert have been eaten away in one year due to the forming of vacua therein.

It has been found that in a culvert having a sharply inclined portion, water dropping freely therein accelerates at the rate of approximately 32.2 feet per second, causing the water to leave the wall of the culvert near the bottom of the descending portion, thus forming a vacuum between the stream of water and the wall of the culvert. The pressure on the stream is relieved at the point where the vacuum is formed and, therefore, the air mixed in the water explodes out of it and, combined with the rarefied air of the vacuum, attacks the side of the culvert. The air thus separated from the water is carried along by the stream but does not mix with it again and, consequently, it accumulates under pressure at the top of the culvert and when the valves are closed a tremendous surge is produced by this trapped air which is quite liable to damage the lock equipment. Even when the air is not trapped in the culvert when the valves are closed vacua therein cause an oscillation of the water which is called water hammer.

Another object of this invention is the prevention of water hammer in culverts.

With these and other objects in view the invention consists essentially of a constriction placed in a culvert having a sharply descending portion, and one or more additional constrictions spaced along the lower portion of the culvert, as more fully described in the following specification and illustrated in the accompanying drawings, in which

Figure 1 is a longitudinal section taken through a culvert extending between two lock chambers.

Figure 2 is an enlarged section taken on the line 2—2 of Figure 1.

Figure 3 is an enlarged fragmentary sectional view taken on the line 3—3 of Figure 1.

Figure 4 is a cross section of a lock chamber, showing the position of the culverts in relation to a lock chamber.

Figure 5 is an enlarged section taken on the line 5—5 of Figure 1.

Figure 6 is an enlarged section taken on the line 6—6 of Figure 1.

Figure 7 is a fragmentary view similar to Figure 1, showing an alternative form of the invention.

Figure 8 is an enlarged section taken on the line 8—8 of Figure 7.

Referring more particularly to the drawings, A is an upper lock chamber, B a lower lock chamber and C a culvert extending therebetween and having a gate valve D. The culvert C has an upper portion 10 communicating with the upper lock chamber A, a sharply inclined portion 11 and a lower portion 12 communicating with the lower lock chamber B.

In the lower portion 12 adjacent the lower end of the inclined portion 11 is placed a constriction 13 which may be formed of concrete, as shown in the drawings, but may be formed of metal or any other suitable material. The constriction 13 is shaped to correspond with the contour of the interior of the culvert and has a central passageway 14 extending therethrough, said passageway being wider at its entrance than at its discharge end. Also placed in the lower portion 12 and spaced from the constriction 13 are one or more additional constrictions 15, one only being shown in the drawings. Each additional constriction is provided with a central passageway 16, said passageway being somewhat larger than the passageway 14 of the first constriction referred to. In the case where more than one additional constriction 15 is employed the passageways 16 may either all be of the same size or they may be progressively increased in size towards the outlet of the lower portion 12 of the culvert. For the purpose of illustration the additional constriction 15 is shown as formed of metal but it may be replaced by a concrete structure.

Adjacent the discharge ends of each of the constrictions 13 and 15 are lateral passes 18 communicating with the lower lock chamber and the culvert. The culvert C may be of any shape but when the bottom thereof is substantially rectangular in cross section as shown in the drawings, said bottom is rounded as at 19 at the side of the culvert opposite the lateral passes 18 adjacent the constrictions 13 and 15.

An alternative form of constriction which may be used in place of the constriction 13 is shown in Figure 7. This constriction comprises a substantially wedge-shaped member 20, the apex of which is adjacent the lower end of the sharply

descending portion 11. A restricted passageway 21 is thus formed between the widest portion of the member 20 and the wall of the culvert.

As stated above, the culvert C may be of any shape, two different shapes being shown in the drawings by way of example. Referring to Figure 4, the culvert shown at 22 is higher and narrower than the culvert shown at 23. In order to obtain the best results it is preferable to use the member 20 in culvert 22 and the constriction 13 in the culvert 23. It may be pointed out, however, that this is not necessary and that the two constrictions may be interchanged if it is so desired.

15 While the device has been described as being used in a culvert extending between two lock chambers, it is to be understood that it may be used in any culvert having therein a sharply inclined portion.

20 The device operates in the following manner:—

When water is rushing through the culvert, the constriction 13 or the member 20 causes a back pressure which extends up into the inclined portion 11, preventing the water from leaving the 25 sides of the culvert, thus avoiding the formation of a vacuum in the inclined portion. As the water is discharged through the constriction 13, which acts as a nozzle, a vacuum normally would be formed around the stream on the side of the 30 constriction remote from the inclined portion. The formation of this vacuum is prevented by the additional constriction 15 which, by causing a back pressure, forces some of the water back towards the constriction 13. At the same time, water entering the culvert through the lateral pass 18 adjacent said constriction, is directed around the stream by the rounded portion 19, completely filling the culvert at this point, thus preventing the formation of a vacuum. The formation 40 of a vacuum adjacent the discharge side of the restriction or restrictions 15 is avoided in the same manner.

By eliminating vacua in the culvert, air mixed with the water cannot explode from it and attack 45 the concrete of the culvert, nor will the air accumulate in the lower portion of the culvert causing tremendous surges when the valves are closed. Also, when there are no vacua in the culvert water hammer is eliminated.

50 From the above it will be seen that means have been provided which will prevent excessive wear on culverts.

Various modifications may be made in this invention without departing from the spirit there- 55 or the scope of the claims, and therefore the exact forms shown are to be taken as illustrative

only and not in a limiting sense, and it is desired that only such limitations shall be placed thereon as are disclosed in the prior art or are set forth in the accompanying claims.

What I claim is:—

1. In a liquid carrying culvert having a sharply inclined portion, means adjacent the lower end of said portion adapted to restrict the flow of liquid therethrough, thereby preventing the formation of a vacuum therein and means for causing a 10 back pressure on the side of the first mentioned means remote from said inclined portion.

2. In a liquid carrying culvert having a sharply inclined portion, at least two constrictions in the culvert below said portions, and means for admitting liquid into the culvert adjacent to and on the side of each of the constrictions remote from said inclined portion, thereby preventing the liquid flowing through the culvert from forming a vacuum at the discharge side of the 15 constrictions.

3. A device according to claim 1, in which the means adapted to restrict the flow of the liquid comprises a substantially wedge-shaped member, the apex of which is adjacent the lower end of 25 the descending portion, thus forming a restricted passageway between the widest portion of said member and the wall of the culvert.

4. In a liquid carrying culvert extending between two lock chambers and having a sharply 30 inclined portion, a plurality of constrictions below said portions having restricted passageways therethrough, the passageway of the first constriction being somewhat smaller than the passageway or passageways of the remainder, and a 35 lateral pass adjacent the discharge side of each constriction communicating with one of the lock chambers.

5. A device according to claim 4 wherein the restricted passageways thereof are progressively 40 larger than the passageway of the first restriction.

6. A device according to claim 4 in which the bottom of the culvert is substantially rectangular in cross section, said bottom being rounded 45 at the side opposite the lateral passes adjacent the discharge side of the constrictions.

7. A device according to claim 4 wherein the restricted passageways thereof are progressively 50 larger than the passageway of the first restriction and in which the bottom of the culvert is substantially rectangular in cross section, said bottom being rounded at the side opposite the lateral passes adjacent the discharge side of the constrictions.

ROBERT A. BRADLEY.
